PROTECTIVE DEVICE

Ernest William Drescher, Manheim Township,
Lancaster County, Pa., assignor to Hamilton
Watch Company, Lancaster, Pa.

Application November 14, 1941, Serial No. 419,145

2 Claims. (Cl. 58—90)

This invention relates to protective devices for timepieces and has particular reference to improved means and method of protecting a timepiece from dust and moisture.

An object of this invention is to provide improved means and method of preventing dust and moisture from entering a timepiece about the stem thereof.

Another object is to provide an improved dust and moisture seal for a timepiece stem, which is adapted to operate efficiently with the stem in either winding or setting position.

Another object is to provide a stem unit as described, which may very readily be disassembled.

Another object is to provide a stem unit as described, in which an efficient dust and moisture seal may be maintained even upon the removal of the crown.

Another object is to provide a protective unit as described, including a sleeve with its bore having a relatively long section in such snug fitting sliding relation with a shaft, and under such resilient pressure along said shaft in the direction of a cap member, as to strongly resist the passage of dust and moisture to the timepiece.

Another object is to provide a dust and moisture seal for a timepiece stem assembly with substantial clearances for the fitting of the stem in the watch case.

Other and further objects will be clearly apparent from the following specifications and from the drawing.

Referring to the drawing:

Fig. I is an elevation of the device embodying this invention, in partial vertical central section;

Fig. II is an illustration of an alternate structure, showing the central portion of Fig. I in different arrangement; and

Fig. III is a plan view of the structure of Fig. I with crown 6 and bow 3 removed.

This invention is directed to dust and moisture sealing in connection with timepiece stem assemblies. It provides a unit which is for practical purposes, dust and moisture proof. The unit is readily assembled and disassembled, and its seal remains efficient in either the setting or winding position. An important feature of the invention is the use of the combination of a long, snug fitting sleeve on the timepiece stem, and a resilient pressure surface contact on a shoulder of the sleeve. Another important feature is the provision of a highly efficient protective unit which not only acts to keep dust and

moisture out of the timepiece but also provides desirably substantial clearances in the fit of the stem within the stem opening of the timepiece case.

5 As illustrated in the drawing the device embodying this invention is mounted on the timepiece housing or watch case 1, of which only a portion sufficient to illustrate the invention is shown. Secured to the case 1 is a support 2 for a bow 3.

The case 1 has an opening 4 through which a stem 5 extends, and a crown 6 is threaded on the upper end of the stem 5.

10 The bow support 2 is provided with an upstanding hollow central hub 7 which is internally threaded to receive a cap member 8 which has a central opening 9 in alignment with the opening 4 in the case 1. The cap 8 is provided with horizontal slots 10, Fig. II, in its top face, so that a screw driver or similar tool may be used to thread the cap 8 in or out of the hub 7.

15 A sleeve 11 is mounted on the stem 5 in snug fitting sliding relation therewith and it is a feature of this invention that while the stem 5 is slideable in the sleeve 11, it has such a snug fit therewith as to strongly resist the passage of dust or moisture. With this arrangement, for example, the stem may be pulled out into the usual position for setting a watch. The sleeve 20 11 has such a snug fitting relation with the stem 5, and this relation extends over such an extensive longitudinal dimension of the stem 5, that the possibility of dust or moisture entering the watch case by passing between the stem 5 and the sleeve 11 is very small.

25 The dimensions of the openings 9 of the cap 8, 12 of the hub 7 and 4 of the case 1 are such as to permit the stem 5 and its surrounding sleeve 11, to be located within those openings with substantial assembly clearances.

30 It is important, from a practical standpoint in the manufacture of watches, that the opening 4 in the case 1 be so located and dimensioned as to permit a substantial tolerance in the location of the stem 5 with respect to that opening. Otherwise, that is, if a precise location were required, it is doubtful whether such precision of fitting and location would be sufficient to exclude dust from the case, and in any event, the 35 manufacture and assembly cost and difficulty would make such an arrangement normally undesirable.

40 This invention provides such desirable clearances and a dust and moisture proofing arrangement which effectively seals the openings formed

thereby. This is illustrated in Fig. I, and it will be seen that there is room to vary the location of the stem 5 with its associated sleeve 11 and crown 6, within the diametric confines of the openings 4, 12, and 9.

In order to prevent dust entering the case between the sleeve 11 and the wall of the opening 4, the sleeve 11 is provided with a flange 13 on its upper end, and this flange is resiliently pressed against the bottom of the cap 8, in surface to surface relation therewith. This resilient pressure is accomplished by means of a spring 14, surrounding the sleeve 11, with its upper end bearing against the under side of the flange 13, and its lower end bearing on a washer 15 which fits snugly about the sleeve 11, and rests on the case 1 so as to cover that part of the opening 4 which remains after the insertion of the stem 5 and sleeve 11.

Consequently, in order to enter the case between the wall of the opening 4 and the sleeve 11, dust must first pass between the top surface of the flange 13 and the bottom surface of the cap 8, which are held together by resilient pressure. Even if the dust did get by these spring pressed surfaces it would still have to pass either between the sleeve 11 and its snug fitting washer 15, or between the spring pressed surfaces of the washer 15 and the case 1.

In addition to the above described barriers, a tortuous passage is provided, through which the dust must pass before it gets to the traps.

The crown 6 is so formed as to surround the hub 7 and to extend well below the upper surface thereof. Consequently dust, to reach the traps described, must first travel beneath the hub surrounding portion of the crown 6, up the outside, across the top, and down the inside of the hub 7. Even with the crown 6 removed, dust or moisture still have barriers to their entrance to the watch case.

It is pointed out that the arrangement of this device is such as to facilitate assembly and disassembly and that the crown 6 may be removed without release of the spring pressure, or diminishing the effectiveness of the major dust and moisture barriers, and the stem 5 may be pulled out to setting position by sliding through sleeve 11, without in any way diminishing the effectiveness of the dust and moisture resistance of these barriers.

The arrangement of this invention provides considerable resistance to the entry of moisture into the case, and when, as is desirable, lubrication is placed between the cap 8 and flange 13 and between the stem 5 and sleeve 11, the resistance to the passage of dust and moisture, is, for all practical purposes, essentially com-

plete. A further step to aid in dust and moisture proofing is the filling of the opening 12 in the hub 7, with heavy grease of the type which resists fluidity, or other suitable packing.

5 An alternate construction is illustrated in Fig. II. This arrangement is designated particularly to increase the protection against moisture, and consists of a packing ring 16, surrounding the stem 5 in snug fitting relation therewith and 10 held between the lower face of the cap 8 and the upper end of the sleeve 11 by the spring 14. The packing ring 16 and the upper end of the sleeve 11 are both cut at such an angle, as at 17, that the packing is forced, by the spring 15 14, both against the cap 8 and against the stem 5.

The unthreaded portion of stem 5 in this arrangement extends upward at least beyond the bottom of the cap 8, and the central threaded hub of the crown 6 is modified to allow for this extension.

What I claim is:

1. A dust cap for watches comprising a watch case having an opening therein, a pendant block formed with a segment of an annular recess and secured to said case and having a threaded opening aligned with said watch case opening, a sleeve having an upper shoulder passing through said case opening, a sealing washer around said sleeve and seating against the case within the threaded opening, a coil spring about said sleeve and resiliently urging said annular shoulder and said washer apart, a screw plug threaded in said pendant block opening and bearing on said sleeve shoulder, a stem slidable in said sleeve and a crown on said stem, said crown being formed with a downwardly projecting rim fitting into the recess of said pendant block.

2. A dust cap for watches comprising a watch case having an opening therein, a pendant block secured to said case and having a threaded opening aligned with said watch case opening, a watch stem passing through said case opening and said pendant opening, a sleeve slidably mounted on said watch stem and formed with an annular shoulder at its upper end, a washer mounted on said sleeve and closing said case opening, a screw plug threaded in said pendant block opening and bearing against said sleeve and a coil spring bearing against said annular shoulder and said washer providing dust proof connection at said case opening, the threaded plug bearing against the upper part of the sleeve serving to adjust the tension of said coil spring, and a crown on said watch stem.

ERNEST WILLIAM DRESCHER.
